[57] CLAIM

The ornamental design for a canopy for a convenience
store food preparation center, as shown and described.

DESCRIPTION

FIG. 1 is a perspective view of a canopy for a convenience store food preparation center showing my new design;

FIG. 2 is a top plan view thereof;

FIG. 3 is a front elevational view thereof, a food preparation center being shown by means of broken lines for illustrative purposes only; and

FIG. 4 is a left side elevational view, the right side being a mirror image thereof.

FIG. 1

FIG. 2**FIG. 4**

FIG. 3
